UNITED STATES PATENT OFFICE.

JOHN HARDY AND WILLIAM N. CLARK, JR., OF BROOKLYN, NEW YORK,
ASSIGNORS TO SAID WILLIAM N. CLARK, JR.

CORNICE-POLE BRACKET.

SPECIFICATION forming part of Letters Patent No. 355,449, dated January 4, 1887.

Application filed July 3, 1886. Serial No. 207,080. (No model.)

To all whom it may concern:

Be it known that we, JOHN HARDY and WILLIAM N. CLARK, Jr., of Brooklyn, in the county of Kings and State of New York, have 5 invented an Improvement in Cornice-Pole Brackets, of which the following is a specification.

Cornice-pole brackets have heretofore been made in two or more parts, so that the cornice-pole can be set out at a greater or less distance from the window-frame. In these cases, however, it has usually been necessary to disconnect the bracket from the window-frame in order to move the cornice-support 15 nearer to or farther from such window-frame.

In our improvement we make use of a bracket that is adapted to being fastened upon the window frame or casing independently of and separate from the extensible cornice-support, so that such support is not liable to become injured in fastening up the bracket, and the cornice-pole can be set farther away from the casing or nearer to the same without making any change in the bracket itself, thus greatly 25 facilitating the proper placing of the cornice-pole to suit the drapery.

In the drawings, Figure 1 is a side view of the cornice-pole bracket. Fig. 2 is a section at the line $\alpha\alpha$, Fig. 1. Fig. 3 is an elevation 30 of the brace. Fig. 4 is a detached view of the screw-rod. Figs. 5 and 6 are elevations of modifications of the bracket portions, and Fig. 7 is an end view of the screw-rod.

The bracket is constructed in any suitable 35 manner, so long as it is adapted to the reception of our improved extension cornice-support.

We prefer, and have represented, the bracket 40 as composed of the screw-rod A and the brace B for supporting the same, the portion A of the bracket being horizontal, or nearly so, and the brace B inclined, and in the bracket there is a hole at C. The bracket is to be secured to the wood-work by the screw 2 at the end 45 of the rod A, and by a screw, 3, passed through a hole at the lower end of the brace B, or said bracket may be secured in any other suitable manner. Through the hole C passes the extensible cornice-pole support E, the same be-

ing in the form of a rod having a semicircular 50 hooked end, 4, and screw 5 for receiving and holding the cornice-pole. At the other end of the extensible support is a clamping-slide, F, the same having a screw, 6, to confine the extensible support in any position to which it 55 may be adjusted. It is generally preferable to make this slide in the form of a metal block with a hole through it for the reception of the inner end of the support E, and a binding-screw, 7, passing through the slide, holds the 60 end of the support and the slide to move together when the parts are made as shown in Figs. 5 and 6. This slide F is free to be moved back and forth upon the bracket-rod A when the screw 6 is 65 slackened, and when the holder has been adjusted to the proper place it is clamped by the screw 6.

It will be seen by the drawings that the end of the bracket-rod A may be turned up for the 70 hole C to pass through it, as in Fig. 5, or it may be turned down, as in Fig. 6, and in this case the hole may pass through the downwardly-bent connection between the rod A and the brace B, as in said Fig. 6, or the end 75 of the rod A may be bent up as an eye, as seen in Fig. 7, to form the hole C, for the support E; but we prefer and use the form of connection shown in Figs. 1, 3, and 4, in which the outer end of the brace B is bent vertically 80 and flattened to receive the hole C for the pole-support E to pass through, and there is a slot, 9, extending from such hole which receives the neck 10 of the screw-rod A, such rod A being flattened at the neck to pass into 85 such slot. The brace B can be used as a wrench in screwing the screw 2 into the wood-work, and after the parts of the bracket are properly in place, including the slide F, the rod of the bracket-support E is to be entered 90 into the hole C and into the slide F, and the latter and the cornice-pole support are held in position by the one screw 6, and the rod E filling the hole C prevents the end of the bracket-rod A slipping out of the notch 9. 95

If desired, the bracket may be inverted so that the brace B passes upwardly instead of downwardly, and in that case the cornice-pole

support E will be partially rotated in the hole C to bring the semicircular end 4 in the proper position.

We claim as our invention—

- 5 1. The combination, with the screw-rod A, of the brace B, the extensible cornice-support E, sliding through the hole C, and the slide F, sliding upon the rod A, and the clamp-screw 6, substantially as set forth.
- 10 2. The bracket formed of the brace B, having the hole C and slot 9 near the end, and

the notched rod A passing into the slot 9, in combination with the extensible cornice-support E and clamping-slide F, substantially as set forth.

Signed by us this 28th day of June, A. D. 1886.

JOHN HARDY.
